UNITED STATES PATENT OFFICE.

EUGENE CONTI, OF JERSEY CITY, NEW JERSEY.

SMOKING DEVICE

Application filed September 29, 1924. Serial No. 740,680.

To all whom it may concern:

Be it known that I, EUGENE CONTI, a citizen of the United States, and a resident of Jersey City, county of Hudson, State of New Jersey, have invented an Improvement in Smoking Devices, of which the following is a specification.

This invention relates to a smoking pipe and the like and more particularly to means for maintaining the same clean and sweet.

In the past, attempts have been made to prevent the passage of the moisture from the tobacco and of the saliva which accumulates in the stem of a pipe, cigar or cigarette holder, into the mouth of the user. These attempts, however, have not produced the desired result but, at most, have simply prolonged the period of use of the pipe without cleaning.

20 However, the device of this invention not only prevents the passage of the moisture into the mouth of the user but at all times keeps the smoke passage of the pipe clean.

In the drawing in which one embodiment of my invention is illustrated—

Fig. 1 is a sectional view of a smoking pipe embodying the invention;

Fig. 2 is an enlarged view of one form of tube which may be used, and

30 Fig. 3 is a sectional view of line 3—3 of Fig. 1 showing the position of the tube within the bore of the pipe stem.

In the embodiment of the invention illustrated, the pipe includes the usual parts, namely, the bowl 1, and the stem having the two parts 2 and 3, through which the smoke passage 4 extends. This smoke passage 4 is enlarged to form a chamber 5. As illustrated in the drawing, this chamber extends into both of the sections 3 and 4 of the stem but it is of course possible to have the chamber located entirely within either of the sections.

40 In order that the moisture from the tobacco and the saliva may be absorbed so that it will not pass to the mouth of the user, and in order that the smoke passage may be kept clean, I have located within the passage and more particularly in the chamber 5, which is formed simply by enlarging the passage, an absorbent and cleaning element 6.

45 In the particular embodiment illustrated in the drawing this element is in the form of a tube which is sufficiently less in diameter than the diameter of the chamber 5.

to permit its movement within the chamber and to permit its being ejected from the pipe after saturation and after separation of the sections 2 and 3 of the stem by a simple blowing out or shaking out operation.

50 As stated, this element 6, which in the form illustrated is a tube but which need not be of such form, may be of various constructions, the essential requirement being that it be of less cross sectional dimension than the chamber 5 so that both of its surfaces will be presented to the smoke as it passes through the stem. I have illustrated the tube as being formed by a strip or strips 70 wound in helical formation and coated with paraffin but it is to be understood that the tube may be otherwise formed and the coating with paraffin may be omitted.

55 Furthermore, because of the fact that the drawing of the smoke through the stem is not dependent upon any cross sectional continuity of the element 6, the latter when in the form of a tube need not be closed, that is to say, it need not be continuous in cross sectional configuration nor of any particular cross-sectional configuration. Therefore, when I speak of the element 6 being a tube, it is not to be understood that it is limited to one which is circular or continuous in 80 cross section, for the cross sectional configuration of the element may be varied within wide limits.

60 Furthermore, if desired the paraffin coating of the element 6 may be entirely omitted, and on the other hand the element may be impregnated with a flavoring compound either in conjunction with or without the paraffin which will impart to the smoke any 90 desired taste.

65 In use, the tube 6 is placed in the chamber 5 of the stem and the stem secured to the bowl of the pipe in the usual manner. The smoke, which is drawn through the stem, will pass through the interior of the tube 6 (when such is used) and will also pass around the exterior of the same so that the moisture from the tobacco is absorbed by both the interior and the exterior surfaces. 100 This results in a quick and complete extraction of the moisture from the smoke and permits the smoke to enter the mouth of the user in a dry condition.

70 Moreover, the saliva which inevitably flows into the pipe stem contacts with the inner and outer surfaces of the tube and by both of these surfaces, the saliva is absorbed 110

and prevented from returning to the mouth of the user.

Because of the fact that the absorbent element 6 is free to move within the chamber 5 it will shift its position within the chamber and continuously present a different or new portion of its surface to the accumulation of saliva in the bottom of the chamber which will completely absorb the saliva. This absorption, of course, is enhanced by the fact that an unsaturated surface is continuously presented to the lower portion of the chamber. The movement of the element 6 thus keeps the chamber clean and free from moisture.

Periodically the element 6 may be removed and replaced by a new and similar element by simply separating the sections of the stem and blowing out or shaking out the absorbent element, which removal will carry with it all of the accumulated moisture and undesirable deposits so that the chamber is left clean for the reception of a new and unsaturated tube.

The element or tube 6 may be made of 25 paper or any other absorbent material and produced at an extremely low cost so that it may be frequently removed and replaced without entailing any considerable expense.

It is of course to be understood that this invention is applicable not only to a smoking pipe but to various other types of smoking devices, such as, for instance, cigar and cigarette holders; and I do not wish the invention to be limited to a smoking pipe.

What I claim is:

1. A smoking device including a stem having a smoke passage extending therethrough and an absorbent tube loosely disposed, throughout its length, within said smoke 40 passage.

2. An absorbent element for a smoking device consisting of a strip of material bent into tubular form.

In testimony whereof, I have signed my 45 name to this specification this 23rd day of September, 1924.

EUGENE CONTI.
